(57) **CLAIM**

The ornamental design for a sock, as shown and described.

DESCRIPTION

This application is related to application Ser. No. 29/907, 120 filed Jan. 4, 2024 which is a divisional of application Ser. No. 29/778,686 filed Apr. 14, 2021 and issued as U.S. Design Pat. No. D1017221 on Mar. 12, 2024 the entire disclosures of which are incorporated by reference herein. This application is also related to application Ser. No. 29/907,138 filed Jan. 4, 2024 which is a divisional of application Ser. No. 29/778,694 filed Apr. 14, 2021 and issued as U.S. Design Pat. No. D1015725 on Feb. 27, 2024 the entire disclosures of which are incorporated by reference herein.

FIG. 1 is a perspective view of a sock in accordance with a first embodiment of our design;

FIG. 2 is a side view (e.g., right side) of the sock in accordance with FIG. 1, with the other side (e.g., left side) being a mirror image thereof;

FIG. 3 is a top view of the sock in accordance with FIG. 1; FIG. 4 is a top view of the sock in accordance with FIG. 1, the top view presenting a two-dimensional view of the design;

FIG. 5 is a perspective view of a sock in accordance with a second embodiment of our design;

FIG. 6 is a side view (e.g., right side) of the sock in accordance with FIG. 5, with the other side (e.g., left side) being a mirror image thereof;

FIG. 7 is a top view of the sock in accordance with FIG. 5;

FIG. 8 is a top view of the sock in accordance with FIG. 5, the top view presenting a two-dimensional view of the design;

FIG. 9 is a perspective view of a sock in accordance with a third embodiment of our design;

FIG. 10 is a side view (e.g., right side) of the sock in accordance with FIG. 9, with the other side (e.g., left side) being a mirror image thereof;

FIG. 11 is a top view of the sock in accordance with FIG. 9;

FIG. 12 is a top view of the sock in accordance with FIG. 9, the top view presenting a two-dimensional view of the design; FIG. 13 is a perspective view of a sock in accordance with a fourth embodiment of our design;

FIG. 14 is a side view (e.g., right side) of the sock in accordance with FIG. 13, with the other side (e.g., left side) being a mirror image thereof;

FIG. 15 is a top view of the sock in accordance with FIG. 13; and,

FIG. 16 is a top view of the sock in accordance with FIG. 9, the top view presenting a two-dimensional view of the design.

The broken lines show portions of the sock that form no part of the claimed design.
